BENJAMIN H. FREEDMAN, OF NEW YORK, N. Y., ASSIGNOR TO HUDSON HOLDING CORPORATION, OF NEW YORK, N. Y., A CORPORATION OF DELAWARE

MATCH PACKAGE

Application filed April 30, 1930. Serial No. 448,453.

This invention relates to an improvement in a package of matches of the form generally known as book matches and has for its object to provide a package which shall be so constructed that the possibility of accident by reason of the package becoming accidentally ignited is avoided.

It is known that many serious accidents have occurred by reason of the fact that the packages of matches in use at the present time are sometimes accidentally ignited during the process of striking a match. The abrasive area or striking surface now provided on the present day form of book match packages is located on the inturned strip at one end of the package and is so positioned that if a match is struck on said surface while the cover flap of the package is open, there is every likelihood of the entire package becoming ignited from the flame of the lighted match.

In many instances also, after a match is struck and while the package is open, the user in shielding the flame of the lit match from the wind with his cupped hands, one of which holds the open package, accidentally brings the package close to the flame of the lighted match with the result that the entire package flares up into flame with serious damage to the hands of the user.

It has been found that the initial cause of many accidents resulting from the sudden and accidental ignition of packages of matches is primarily due to the location of the match-striking surface placed on the package and the position of the matches in the package with respect to such surface. Said surface as it is placed at the present day is so positioned that it permits matches to be struck upon it while the package is open and the matches contained in said package are fully exposed to the possibility of ignition from the lighted match.

One of the objects therefore of this invention is to provide a match package in which a match striking surface will be so located that regardless of how a match is ignited on said surface, the flame of the ignited match

50 will be prevented from coming into contact

with the matches contained in the package by the covering of the package.

A further object of this invention is to provide a match package in which a match-striking surface is incorporated, which surface shall be so located that the package must be held in a certain position to permit ignition of a match through the use of said surface, whereby the matches in the package will be held with their ends furthest from the flame of the match so that the possibility of flame from the ignited match reaching the match heads and accidentally igniting the matches contained in the package is avoided.

A still further object of the invention is to provide a match package wherein the matches contained within the same are held in a different relationship with respect to the outer covering of the package than those of the past have been held.

Through the particular arrangement of the matches and the covering for the same, I provide a match package having a maximum of safety. The package is so constructed that a match cannot be struck until the cover is closed and when the cover is closed, the igniting surface is positioned so remotely with respect to the match heads that it is, 80 practically impossible for a flame from the lighted match to reach the heads of the matches and accidentally ignite the package.

With these objects and such other objects as may hereinafter appear, in view, I have 85 devised the particular arrangement of parts hereinafter set forth and more particularly pointed out in the claim appended hereto.

Reference is to be had to the accompanying drawing forming a part hereof in which

90 Figure 1 is a plan view of my improved match package with the paper covering of the same spread out flat to disclose the arrangement of the match strip;

95 Figure 2 is a face view of the match strip removed from the package in order to fully disclose its fastening flaps; and

Figure 3 is a perspective view of the complete match package in closed condition.

Throughout the various views of the draw- 100

ings, similar reference characters designate to cover all structures coming within the scope of the annexed claim.

In the embodiment of my invention disclosed in the accompanying drawing, 1 indicates the outer paper covering of the match package. The same consists of an elongated strip of cardboard or of some similar material. The strip 1 is provided with a transverse fold line 2 which divides it into a body portion 3 and a cover flap 4.

The body portion 3 has its end folded inwardly as at 5 to provide an inturned fastening flap 6 under which a flap 7 provided on the match strip 8 is held by means of a staple 9. The fastening staple 9 passes through the inturned strip 6, the fastening flap 7 on the match strip and finally, through the body portion 3 of the cover. The match strip 8 is preferably composed of two or more layers of matches 12, said matches having their heads 13 positioned remote from a striking surface 14 provided on the outer face of the cover flap 4.

When the cover flap 4 is in its closed position as disclosed in Figure 3, it will be seen that the striking surface 14 provided on the outer face of the cover flap 4, forms an elongated area of an abrasive material located adjacent to the edge of the package that is situated remote from the match heads 13. Thus, when the package is held for the purpose of striking a match, the heads of the matches are far away from the flame and are fully protected by the covering of the match package. It is not possible to strike a match on the abrasive surface 14 with the match package held open since no support is provided behind the same while the flap is open. The match heads in the package are not only protected from the flame of the ignited match during the process of lighting the match, but also while the match and the package are held in the cupped hands while the cigarette is being lit.

At 15 is shown a side flap formed on the match strip, the same being similar in general outline and construction to the side flap 7 disposed at the opposite edge of the strip. The flap 15 fits under the cover flap 4 adjacent its point of joinder to the body portion 3 and the staple 16 extends through the cover flap 4 and through the flap 15 provided on the match strip.

Thus, the two opposite sides of the match strip are attached to the cover member by means of the staples 9 and 16 passing through the flaps 7 and 15 respectively in the match strip. The match strip is thus secured firmly in position in such a manner that it is impossible for the igniting strip 14 to, by any process of distortion of the cover flap, come in contact with the match heads.

Having described one embodiment of my invention, it is obvious that the same is not to be restricted thereto but is broad enough

What I claim is:—

A match package provided with a match strip having a flap disposed along each of two of its longitudinal parallel edges, a cover containing said match strip, said cover having a narrow inturned flap at one of its ends adapted to overlie one of the flaps on the match strip, a wider cover flap extending transversely of the match strip and adapted to have its end removably tucked under the narrow flap, said wider cover flap overlying the second flap on the match strip, means for attaching each of the two flaps on the cover to each of the flaps on the match strip which they respectively overlie and a striking strip on the outer face of the wider cover flap located adjacent to one of its edges.

Signed at the city, county, and State of New York, this 29th day of April, 1930.

BENJAMIN H. FREEDMAN.
